UNITED STATES PATENT OFFICE.

JOHN W. FOWLER AND DANIEL F. LEWIS, OF BROOKLYN, NEW YORK.

FARE-REGISTER.

SPECIFICATION forming part of Letters Patent No. 391,702, dated October 23, 1882.

Application filed November 15, 1882. Renewed March 16, 1886. Serial No. 195,481. (No model.)

To all whom it may concern:

Be it known that we, JOHN W. FOWLER and DANIEL F. LEWIS, citizens of the United States, residing at Brooklyn, in the State of New York, have invented a new and useful Improvement in Fare-Registers, of which the following is a specification.

This invention is additional to the improvements in fare-registers heretofore patented by us and embodied in our duplex register known as the "alarm."

In the specification forming part of our Patent No. 247,553, dated September 27, 1881, with the aid of references to our specifications forming part of Patent No. 247,552, of same date, (application filed October 23, 1880,) and Patent No. 231,161, dated August 17, 1880, we describe an improved "alarm" register having, in combination with its trip-register, a reciprocating device or setting mechanism for resetting said register at zero at the end of each trip, an indicator mechanism for displaying a trip-signal actuated by said setting mechanism in said act of resetting the trip-register, and a bell mechanism which interlocks with said indicator mechanism for preventing repeated actuations of the trip-signal during individual setting operations, and does not release the same until after another unit has been registered and in the act of attesting such registration by a stroke on the bell. Moreover, the species of setting mechanism described in said Patent No. 247,553, and claimed in said Patents No. 247,552 and No. 231,161, comprise in each a "setting-hub," by which the trip-hand of the register is carried, and a reciprocating "setting-slide," by which the former is rotated to reset the trip register, said setting-hub having three tangential "arms" attached by pivots and thrown outward by springs to coact with a pair of "cams" on said setting-slide, while the latter is provided with a guard-flange constructed with ratchet-teeth and engaged by a guard-pawl to insure complete strokes of the setting slide, which construction precludes leaving the trip-hand elsewhere than at zero or at one of two intermediate stopping-points on the main dial by means of the setting device.

The present invention consists in certain novel parts applied to a setting-hub and a set-

ting-slide of the aforesaid description and in peculiarly-secured springs for throwing out the arms of said setting-hub, together with certain novel combinations formed by the addition of said parts, as hereinafter described and claimed.

The object of the first part of this invention is to cause the indicator mechanism to be actuated in the final act of turning the trip-hand to zero, and not before, so as to preclude changing the indication of the trip signal without at the same time completing the resetting operation.

The distinctive object of the second part of this invention is to arrest the trip-hand at zero when it is turned back by means of the setting mechanism without interfering with its progression beyond zero in the registering operation (as described in J. W. Fowler's specification forming part of Patent No. 185,740, dated December 26, 1876, and in our Patents No. 190,021, dated April 24, 1877; No. 206,553, dated July 30, 1878, and No. 207,728, dated September 3, 1878) by means of a concealed "zero-stop" of novel construction adapted to our said reciprocating setting-slide.

The object of the third part of this invention is to provide the setting-hub with more durable springs for projecting its arms, the use of solder for securing the springs being dispensed with.

Figure 1 of the drawings accompanying this specification is a small face view of an alarm register illustrating this invention. Fig. 2 is a face view of the same on a larger scale with the case and dials removed and the parts at rest in the positions indicated by full lines in Fig. 1. Fig. 3 is a like face view of the upper part of the works, showing the parts in full lines at rest as they appear when the trip-register is reset at zero, the said unlocking of the trip-signal being illustrated by dotted lines. Fig. 4 is a horizontal section through all, showing an elevation of the indicator mechanism from beneath; and Fig. 5 is a vertical longitudinal section through all, showing, as does the former, the parts in the same positions as in Fig. 2. Fig. 6 is a perspective view of the top plate of the setting-slide and the new parts attached thereto. Fig. 7 is a perspective view of the setting-hub, showing its new parts; and

Fig. 8 is a bottom view of the latter, showing its arm-springs.

Like letters refer to corresponding parts in the several figures, correspondingly-numbered 5 arrows indicate the respective motions of the principal parts, and broken lines 4 4 and 5 5 across Figs. 1 and 2 indicate the planes of the respective sections.

Excepting the new parts and arm-springs 10 above referred to and certain details of construction, the improved register is identical with the one shown in our Patent No. 247,553, aforesaid. Referring, therefore, to our specification forming part of said Patent No. 247,553 15 and to those of our other patents therein referred to for fuller descriptions of the parts described and claimed therein, the present specification will be chiefly confined to a description of those features and combinations of 20 parts hereinafter claimed as new.

In the said drawings accompanying this specification, as in those of our said Patent No. 247,553, A represents the units-shaft of the "trip-register;" B, that of the "permanent 25 register;" H, the trip-hand of the former; H², the corresponding index-hand on said shaft B; C, the hundreds-shaft, and H³ the rotary hundreds-dial; S, the main actuating-slide; F, the main pawl carried by said slide; R, the main 30 ratchet-wheel, and A' its shaft; P W W², gearing connecting said shafts A', A, and B for the transmission of registering impulses to the index-hands H H², and through a cam on the wheel W² and coacting mechanism to said 35 shaft C and hundreds-dial H³, and X^a the detent-pawl of said ratchet-wheel.

I represents the setting-hub, J the setting-slide, and K, Fig. 1, the push-key, of the setting mechanism.

40 V represents the trip-signal, Z the rotary shaft, Y the rock-shaft, U the spring-detent, and T the lock-arm, of the indicator mechanism; and E represents the distinct bell-lever, D the "catch," and G the gong-bell, of the bell mechanism.

45 In mentioning other parts we shall not confine ourselves to reference-letters heretofore used.

Said mechanisms, as in all our registers, are 50 mounted upon a back plate, b, with the aid of frame-pieces f f² f³ f⁴, attached to the face of the back plate, the whole being inclosed by a circular case, c, having a glass front plate and attached by screws to the edge of said back 55 plate, while all, except the hands H H², are arranged behind a dial-plate, d, having dials concentric with the respective units-shafts carrying said hands and apertured for exposing respectively the successive indications of the 60 hundreds-dial H³ and the trip-signal V, as shown in Figs. 1, 4, and 5.

Our indicator mechanism has been modified in construction, as will be seen by comparing Figs. 4 and 5 with the figures correspondingly numbered in our said Patent No. 247,553. We now prefer to mount the said trip-signal shaft Z and rock-shaft Y in a single frame-casting

or "bracket," f⁴. The trip-signal V is by preference cylindrical. The detent U is attached to said bracket f⁴ and engages with the 70 same square as the stop-finger or notch of the transmitting-arm m. The lock-arm T is recessed, so as to accommodate a longer spring-finger, and the main lever-arm l is made angular in cross-section at its end or squared on 75 its left-hand side, as shown in Fig. 4, in view of the new mode of operation. The castings of the setting-slide J are so shaped as never to come in contact with said lever-arm l, and the interlocking catch e of the bell mechanism is 80 preferably formed separately (of steel) and attached by a screw to the projection on the body of the bell-lever E, which, primarily, carries the bell-hammer h, as shown in Figs. 4 and 5.

Other details of the indicator mechanism, 85 setting mechanism, and bell mechanism, together with those of the registering mechanisms and main actuating mechanism, are substantially unchanged, excepting the said "new parts" and "arm-springs," which will now be 90 described with references more particularly to Figs. 6, 7, and 8, in which the same are specially shown, as aforesaid.

Two little levers, j j², Figs. 2, 3, 5, and 6, are arranged upon the front or "top" of the 95 setting-slide J at its left-hand edge, and are attached to its top plate by pivotal screws s, so as to work in a plane parallel to said top plate and coupled together by a pin and slot, p, so as to work in unison. The second of these levers, j², terminates in a "head," k, and is bent, so as to project backward and toward the line of the lever-arm l of the indicator mechanism, (represented in Fig. 6,) but in normal position, as shown in Figs. 2 and 6, does not extend to said line. A little spiral spring, s^x, is attached to a hook-extension of the first lever, j, and tends to hold the levers j j² in normal position with said head k out of line with said lever-arm l. To move said head k into line 100 with said lever-arm l, a cam, i, Figs. 2, 3, 5, and 7, in the shape of a concentric integral projection on the sleeve portion of the setting-hub I, is so located on the latter and so proportioned to said levers as to come in contact with 105 the lever j and effect said movement of the head k during the motion of the setting-hub in moving the trip-hand forward to zero from 99. The cam i is extended around said sleeve portion of the setting-hub I about thirty-nine 110 one-hundredths of its circumference, so as to hold said head k in its "projected" position until the setting-hub has turned to the end of that part of its rotation which corresponds with the last reciprocation of the setting-slide 115 J in the resetting operation. In other words, said cam i is adapted to maintain said position of the head k until the second of the setting-hub's arms (now lettered, respectively, a' a² a³, in the order in which they leave a given point 120 in the registering operation) has passed or is passing out of reach of the cams b^a b^b on the setting-slide, so that a single reciprocation of the latter will no longer suffice to turn the

125

130

135

140

145

150

trip-hand back to zero. In reverse order said cam *i* begins to act when the setting-hub is turned backward in the resetting operation to the beginning of that part of its rotation which 5 corresponds with said last reciprocation of the setting-slide.

To prevent turning the trip-hand backward beyond zero by the setting mechanism without limiting its progression in the registering 10 operation, as aforesaid, the setting-slide *J* is provided with a supplemental piece, *j*³, Figs. 2, 3, and 6, attached to its front or top at its right-hand edge by longitudinal pivots and held in effective position by the said spiral 15 spring *s*^x, which is stretched between a stud-pin on this piece *j*³ and the said lever *j*. A stud-pin, *a*, Figs. 2, 3, and 7, is securely fixed in the first of said arms, *a'*, of the setting-hub, so as to project across the main plane of said 20 piece *j*³. A "zero stop," *z*, in the form of a notch, is cut in the inner edge of said piece *j*³ in the path of said pin *a*, as illustrated in Fig. 6, and said edge of the piece *j*³ is continued concentric with said path, and an upturned 25 "toe," *y*, is formed in this line to provide for lifting said piece *j*³ by means of said stud-pin *a* when it approaches in the opposite direction in the registering operation. Said inner edge of the piece *j*³ is further constructed with 30 an incline, *x*, extending from the zero-stop *z* to the inner line of the contiguous cam *b*^a of the setting-slide, so as to throw the point of said arm *a'* out of the path of the cam *b*^a should the reciprocation of the slide be continued, 35 which prevents straining the parts. The said arm-springs are represented by *s*^a in Figs. 5 and 8, and are clearly shown in the latter figure. They consist of pieces of flat steel wire bent to the shape represented and held 40 in place within the annular recess in the back of the setting hub *I* by headed stud-pins *o* in connection with the central boss of the hub within said recess without the aid of solder. Their inner ends are curved to embrace said 45 boss and together extend around the same. Their outer ends, which engage with the stud-pins on the arms, are straight, and their intermediate bends are occupied by the said stud-pins *o*, the heads of the latter precluding ac- 50 cidental displacement, while nearly the whole length of each spring is rendered effective and soldering is dispensed with.

The operation of the improved register is, in brief, as follows: The slide *S* of the main 55 actuating mechanism is reciprocated, as illustrated by arrows 1, 2, by any preferred "pulling device," illustrated by a strap and bell-crank lever at *L*, Fig. 1, and the retracting-spring of said slide. At each completed out- 60 ward stroke (1) a registering impulse is transmitted to the units-hands *H* *H'*, as illustrated by arrows 3, and during each return-stroke (2) the bell mechanism is actuated, as illustrated by arrows 4^a and 4, to attest the registration 65 by a single stroke on the bell *G* as the parts come to rest, false strokes of the bell being prevented by catch *D*. As each hundred is

registered by the units-hand *H*² of the permanent register, the hundreds-dial *H*³ is turned one step, as illustrated by arrows 5, 6, 70 and 7. At the completion of each "trip," the "trip-hand" *H* is set back to zero, as illustrated by arrow 8, this being accomplished by one or, at most, three reciprocations of the setting-slide *J*, imparted in the example by a 75 push-key, *K*, Fig. 1, and retracting-springs *s*^b, the completion of each stroke being insured by the guard-pawl and guard-flange belonging to said setting-slide, which are represented, respectively, by *q* and *r*. At the first 80 inward stroke, (represented by arrow 8^a,) supposing the trip-hand to have advanced beyond 83, but not to 100, as in the example illustrated by Figs. 1, 2, 4, and 5, the cam *b*^a of the setting-slide comes in contact with the arm 85 *a'* of the setting-hub and moves the trip-hand to the end of the first sixth of a backward rotation, (indicated by a single dotted line in Fig. 1,) and the cam *b*^b will act in the return-stroke 8^b upon the arm *a*², leaving the trip-hand at 90 the first of its two "intermediate stopping-points" aforesaid, as represented by dotted outline in Fig. 1. During the next reciprocation of the setting slide said cam *b*^a acts on the arm *a*², and said cam *b*^b on the arm *a'*. At 95 the end of this movement the cam *i* on the setting-hub *I* comes in contact with the lever *j* and moves the lever *j*² so as to set the head *k* in line with the lever-arm *l*. (See Figs. 6 and 7.) The trip-hand *H* is now at its second 100 intermediate stopping-point, as shown in dotted outline in Fig. 1. Another inward-stroke, 8^a, of the setting slide causes the cam *b*^a to act on the arm *a*² and the head *k* to act on the lever-arm *l*, changing the indication of 105 the trip-signal *V* from "up" to "down," for example, and bringing the trip-hand *H* to the end of the fifth sixth of its backward rotation, as illustrated in Fig. 1. Independently of the will of the "setter" the resetting operation is 110 now completed by the action of the retracting-springs *s*^b of the setting slide, the cam *b*^b in the final stroke acting upon the arm *a*² of the setting-hub and bringing the arm *a'*, which bears the stud-pin *a*, into the position in which 115 it is shown in Fig. 3, where said stud-pin is embraced by the zero-stop *z*, and farther backward movement of the setting-hub is prevented. Should the reciprocation of the setting-slide be continued, the pin *a* rides back 120 and forth upon the incline *x* and the outer surface of the cam *b*^a and strain of the parts is precluded. The trip-signal is locked, as shown in full lines in Fig. 3, as soon as its indication 125 is changed, so that repeated actuations thereof during a given resetting operation are precluded. It is unlocked in the act of tripping the bell-lever after the registration of another unit, as illustrated by dotted lines in Fig. 3. Its movements are represented by arrows 9, 130 10, and 11, Fig. 5.

We have thus described our present invention as embodied in our own register, so that those skilled in the art may fully understand

and be enabled to practically apply the same. We do not, however, limit ourselves to this embodiment of the respective features and combinations hereinafter claimed, nor to mechanical details which are not essential to the construction and operation of said features and combinations, respectively. Neither do we claim herein anything shown and described in our patents aforesaid.

10 We claim as new and desire to patent under this specification—

1. The combination, with the setting-hub I and setting-slide J, of the cam *i*, levers *j* *j*², and spring *s*^x, substantially as shown and described.

15 2. The setting-slide J, provided with the coupled levers *j* *j*², terminating in a head, *k*, and with the retracting spring *s*^x, in combination with the setting-hub I, having a cam to move said levers for adjusting said head, and a trip-signal mechanism adapted to be actuated by said head so adjusted when said setting-slide is reciprocated, substantially as herein specified.

20 3. In combination with the trip signal V and mechanism for transmitting motion thereto, the setting-slide J, carrying a laterally-movable head, *k*, adapted to actuate said mechanism when in a given position, and mechanism for moving said head into said position during a given reciprocation of said setting-slide, substantially as herein specified.

25 4. The combination, in a fare-register, of a trip-hand adapted to be reset at zero independently of the main actuating mechanism, setting mechanism comprising a reciprocating setting-slide adapted to leave the trip-hand only at zero and certain fixed intermediate stopping-points, a trip-signal, and mechanism for actuating said trip-signal during the final reciprocation of said setting-slide which leaves the trip-hand at zero, substantially as herein specified.

30 5. The combination, in a fare-register, of a trip-hand adapted to be reset at zero independently of the main actuating mechanism, setting mechanism comprising a reciprocating setting-slide adapted to leave the trip-hand only at zero and certain fixed intermediate stopping-points, a trip-signal, mechanism for actuating said trip-signal during the final reciprocation of said setting-slide which leaves the trip-hand at zero, and means for locking the trip-signal against repeated actuations during a given resetting operation, substantially as herein specified.

35 6. The combination, in a fare-register, of a trip-hand adapted to be reset at zero independently of the main actuating mechanism, setting mechanism comprising a reciprocating setting slide adapted to leave the trip-hand only at zero and certain fixed intermediate stopping-points, a trip-signal, mechanism for actuating said trip-signal during the final reciprocation of said setting-slide which leaves the trip-hand at zero, means for locking the trip-

signal against repeated actuations during a given resetting operation, and means for striking the bell in the act of unlocking the trip-signal, substantially as herein specified.

7. The combination, in a fare-register, of a trip-hand adapted to be reset at zero independently of the main actuating mechanism, setting mechanism comprising a reciprocating setting-slide adapted to leave the trip-hand only at zero and certain fixed intermediate stopping-points, a trip-signal, mechanism for actuating said trip-signal during the final reciprocation of said setting-slide which leaves the trip-hand at zero, means for locking the trip-signal against repeated actuations during a given resetting operation, and means for permanently registering another unit and striking the bell in the act of unlocking the trip-signal, substantially as herein specified.

75 8. The combination, with the setting-hub I and setting-slide J, of the stud-pin *a* on one of the arms of the former and the pivoted supplemental piece *j*³, attached to the setting-slide by pivots and constructed with the zero-stop *z* and lifting-toe *y*, substantially as shown and described.

9. The setting-slide J, provided with the pivoted supplemental piece *j*³, having the zero-stop *z*, lifting-toe *y*, and guard-incline *x*, the latter arranged and operating with reference to the cam *b*^a of said setting-slide, as described, in combination with the setting-hub I, having pivoted arms, one of which is provided with a stud-pin, *a*, to coact with said pivoted piece, substantially as set forth.

10. The combination, with the setting-slide J, of the lever *j* and pivoted supplemental piece *j*³, with the spring *s*^x, common to both, substantially as shown and described.

105 11. The combination, in a fare-register, of a trip-hand adapted to be turned backward to reset it at zero, a trip-signal for actuation at the end of each trip, setting mechanism provided with a zero-stop and comprising a reciprocating setting-slide which carries a movable head adapted to actuate said trip-signal during the reciprocation of said setting-slide which completes the resetting operation, and means for adjusting said head and holding it in effective position during the period corresponding with the resetting scope of said reciprocation of the setting-slide, substantially as herein specified.

110 12. The combination, in a fare-register, of a trip-hand adapted to be turned backward to reset it at zero, a trip-signal for actuation at the end of each trip, setting mechanism provided with a zero-stop and comprising a reciprocating setting-slide with retracting-springs 115 for automatically imparting to said setting-slide its last effective stroke, and means carried in part by said setting-slide for actuating said trip-signal during the setting-stroke immediately preceding said last stroke, substantially as herein specified.

13. The combination, in a fare-register, of a

- trip-hand adapted to be turned backward to reset it at zero, a trip-signal for actuation at the end of each trip, setting mechanism provided with a zero-stop and comprising a reciprocating setting-slide with retracting-springs for automatically imparting to said setting-slide its last effective stroke, means carried in part by said setting-slide for actuating said trip-signal during the setting-stroke immediately preceding said last stroke, and means for locking said trip signal against repeated actuations during a given resetting operation, substantially as herein specified. 15
14. The combination, in a fare-register, of a trip-hand adapted to be turned backward to reset it at zero, a trip-signal for actuation at the end of each trip, setting mechanism provided with a zero-stop and comprising a reciprocating setting-slide with retracting-springs for automatically imparting to said setting-slide its last effective stroke, means carried in
- part by said setting-slide for actuating said trip-signal during the setting-stroke immediately preceding said last stroke, a bell mechanism adapted to lock said trip signal against repeated actuations during a given resetting operation, and the main actuating mechanism of the register as means for unlocking said trip-signal after another unit has been registered, substantially as herein specified. 25
15. The combination, with the pivoted tangential arms of the setting-hub I, of the unsoldered arm springs s^a of bent wire and the headed stud-pins o for retaining the same within the recessed back of said setting-hub, substantially as shown and described, for the purposes herein set forth. 30
